BIRD FEEDER

Maxwell Berry, 2887 Howell Mill Road NW,
Atlanta, Ga. 30327

Filed Dec. 23, 1970, Ser. No. 26,633

Term of patent 14 years

Int. Cl. D30—03

U.S. Cl. D30—14

FIG. 1 is a side elevational view of a bird feeder showing my new design;

FIG. 2 is a front elevational view thereof;

FIG. 3 is a top plan view thereof; and

FIG. 4 is a partial top perspective view thereof taken on line 4—4 of FIG. 1 in the direction indicated.

I claim:

The ornamental design for a bird feeder, as shown.
